UNITED STATES PATENT OFFICE.

JOHN R. WARREN, OF GRAND RAPIDS, MICHIGAN.

INTERNAL-COMBUSTION ENGINE.

1,092,787.

Specification of Letters Patent.

Patented Apr. 7, 1914.

Original application filed July 9, 1910, Serial No. 571,118. Divided and this application filed April 22, 1911. Serial No. 622,754.

To all whom it may concern:

Be it known that I, JOHN R. WARREN, a citizen of the United States, residing at the city of Grand Rapids, in the county of Kent and State of Michigan, have invented new and useful Improvements in Internal-Combustion Engines, of which the following is a specification.

My present invention relates to internal combustion engines, and its object is to provide an improved valve mechanism for such engines, which shall be simple and economical in construction and effective in operation. This object is attained by, and 15 my invention finds an embodiment in, the following mechanism, illustrated by the accompanying drawings, in which—

Figure 1 is a vertical transverse sectional view of an engine illustrating my valve mechanism applied thereto, and taken on an axial plane of a cylinder of the engine; Fig. 2 is an enlarged detail view, showing one of the cam shafts (in cross-section) carrying the valve-operating cams, and connected means for actuating the same; Fig. 3 is an enlarged detail view, in vertical section, of the valve rod's arm for operating the valve, with connected parts, and Fig. 4 is a view showing in perspective the two cam shafts carrying the valve-operating cams, etc., and illustrating diagrammatically the valves, etc.

In the structure shown, the cylinder 1 of my engine is that one, of four of the same construction and dimensions, which appears in Fig. 1, and is nearest the viewer, the other three being beyond and hidden by it. The combustible charge is drawn through a suitable supply pipe 7 communicating 35 with passages 6 respectively controlled by the valves 2, 3, 4 and 5, one for each cylinder, the valve 2 controlling the supply to cylinder 1. Into the main exhaust pipe 8 leads the exhaust passages 9 respectively 40 controlled by the valves 10, 11, 12 and 13, one for each cylinder, the valve 10 controlling the exhaust passage 9 of cylinder 1. Supplemental exhaust passages or vents 14, one in the lower end of each cylinder body, 45 discharge as through a supplemental exhaust pipe 15 into the main exhaust pipe 8. The pistons 16 of the several cylinders are in form an inverted cup, as shown. On the transverse journal 17 of each piston rocks 50 its connecting rod 18, and in a suitable box

19 on said rod's lower end is journaled the crank-pin 20 of its crank on the main shaft 21. The crank-pins for the several cylinders are diametrically oppositely disposed on the shaft, and alternately, the crank-pin 60 of cylinder 1 being shown in full lines in Fig. 1, the crank-pin of the next cylinder appearing in dotted lines, the crank-pin of the third cylinder alining with that of the first, and the crank-pin of the fourth 65 alining with that of the second cylinder. On said transverse journal 17 of the pistons also rock valve-actuating connecting rods 22 and 23, one of each for each pair of cylinders, for actuating, one—22—the supply controlling valve, and the other—23—the main exhaust valve of each cylinder. The lower ends of these connecting rods are pivoted, the rods 22 to their respective lever arms 24, and the rods 23 to their respective 70 lever arms 25, said lever arms 24 turning on the left-hand cam-shaft 26 (as shown in Fig. 1) and the lever arms 25 on the right-hand cam-shaft 27; the valves, lever-arms, cam-shaft, etc., on the left hand of the 75 structure thus governing the combustible supply and the similar parts on the right hand governing the exhaust. It will be seen that the two connecting rods 22 actuating the supply valve mechanism are connected 80 to pistons whose crank pins are 180 degrees apart: and similarly, that the connecting rods 23 actuating the exhaust valve mechanism are connected to pistons whose crank pins are 180 degrees apart. Each lever arm 85 carries a pallet 28, spring-pressed at 29 and adapted to engage either of the two diametrically oppositely disposed ratchet teeth 30 or 31 of the ratchet wheels 32 keyed on the left-hand, and 33 keyed on the right-hand, cam-shaft. These cam-shafts respectively carry cam-arms 34 and 35, each 90 adapted to engage at a point in its revolution and to actuate respectively the valve rods 36 and 37, as by means of anti-friction rollers 38 carried on the slotted ends 39 of the valve-rods. These cams by the revolution of the cam shafts engage the rollers 38 and thereby lower the valve rods 36 and 37 to operate the valves. Through the slotted ends 39 of the valve rods pass the cam shafts 26 and 27 respectively, the slot in such ends being elongated sufficiently in a vertical direction to accommodate the movement of the valve rods.

Suitable springs 40 pressing the collars 41 on the stems of the supply and main exhaust valves, hold the upper ends of such stems tightly against horizontal arms 42 of the 5 several valve-rods and in depressions 43 in such arms, as shown in Fig. 3. The action of these springs is to raise the valves to close them, until the revolution of the cam-arms moves the valve rods against the pressure of such springs and of the springs 44 to open such valves.

The valves and their controlling and actuating means are so adjusted that the piston, etc., of each cylinder operates as follows: When the piston is at its highest point (as shown in Fig. 1 and having reference particularly to that figure), its main exhaust valve 10 is closed, and so, by the position of the lower part of the piston, is the supplemental exhaust passage 14. The supply valve 2 is open. As the piston descends, the combustible charge is drawn in through the supply passage 6. When the piston reaches its lowest point the supply valve's ratchet wheel 32 is moved by its pallet a quarter-way around, thus closing the supply valve. As the piston ascends the charge is compressed inside the cylinder. The charge is then fired in the usual manner, forcing the 20 piston down a second time; when it reaches its bottom point the auxiliary exhaust passage 14 is thus opened (the piston having descended below it), and, by its ratchet wheel 33, etc., the main exhaust-valve 10 is also opened through which the ascent of the piston expels the products of combustion. The two ratchet teeth of the ratchet wheel, actuated by one piston, are positioned a quarter-way around the shaft from the teeth 25 in the other wheel on the same shaft actuated by another piston; so that, although each pallet turns its ratchet wheel only a quarter-way and engages it only alternate movements of the pallet's lever arm, yet the cam-shaft is turned a quarter-way around by the pallet of the other cylinder and left in position for the first-named cylinder to operate it its next movement: this quarter-way arrangement of the ratchet wheels' teeth is 30 seen in Fig. 4, in which figure the position of the various valve-seats is diagrammatically shown by dotted horizontal lines 45. The like disposition of the teeth of the ratchet wheels is made as to both the cam- 35 shafts 26 and 27, and it will be seen that the means for, and method of, actuating the supply valves and the main exhaust valves are the same in arrangement and operation; and the sequence of their action is preferably 40 such that the charge in the first cylinder, beginning at one end of the machine, is first fired, then the third, then the second and lastly the fourth, thus preventing over-heating 45 of the water where the water-jackets surround the cylinders in pairs.

It will be seen that the valves are operated by the piston directly and not indirectly through the main shaft by means of gears or in any other manner. The piston therefore has the same effect on the valves, whichever 70 direction the main shaft is turning. The direction of such shaft's rotation is governed, and may be reversed, by timing the firing of the charge to the position of the main connecting rod 18 on one side or the 75 other of its "dead center"; and in any case each of the cam-shafts continues to rotate in the same direction.

Other parts shown on the drawings are indicated by the following reference characters, viz.: 46, bearing for the main shaft: 47, bolts connecting the supply and exhaust pipes to the cylinders: 48, the water jacket: 49 casing: 50, valve cages: 51 retaining means therefor.

This application is division 2 of my pending application Serial No. 571,118, filed July 9, 1910, and divided as required by the Patent Office: and certain features herein shown are the subjects matter of my copending applications for patent.

My invention may manifestly be embodied in different and varying construction without departing from its spirit; and I do not propose to confine myself to the construction shown and described.

I claim:

1. In an engine, the combination with a plurality of engine cylinders each having a piston, a supply valve and an exhaust valve, 100 of a rotatable shaft, means to successively operate the supply valves and actuated by the rotation of the shaft to a certain rotary position for each supply valve, means actuated successively by the pistons to intermittently turn the shaft successive portions of its movement to its several valve-operating positions; a second rotatable shaft, means to successively operate the exhaust valves and actuated by the rotation of the second shaft 105 to a certain rotary position for each exhaust valve, means actuated successively by the pistons to intermittently turn the second shaft successive portions of its movement to its several valve-operating positions and in 110 engine-operative relation to the position of the first shaft.

2. In an engine, the combination with two pairs of engine cylinders each cylinder having a piston, a supply valve and an exhaust valve, of a rotatable shaft carrying ratchet wheels, each wheel having two teeth, means to successively operate the supply valves and actuated by the rotation of the shaft to a certain rotary position for each supply 120 valve, means actuated by alternate movements of each of a pair of pistons to engage a tooth of a ratchet wheel to turn the shaft successive portions of its movement to one of its valve-operating positions; a second 125

130

rotatable shaft carrying ratchet wheels, each wheel having two teeth, means to successively operate the exhaust valves and actuated by the rotation of the second shaft to a 5 certain rotary position for each exhaust valve, means actuated by alternate movements of each of a pair of pistons to engage a tooth of a ratchet wheel to turn the second shaft successive portions of its movement to 10 one of its valve-operating positions, and in engine-operative relation to the position of the first shaft.

3. In an engine, the combination with a plurality of engine cylinders each having a 15 piston and a valve, of a rotatable shaft, means to successively operate the valves and actuated by the rotation of the shaft to a certain rotary position for each valve, and means actuated successively by the pistons 20 to intermittently turn the shaft successive portions of its movement to its several valve-operating positions.

4. In an engine, the combination with a plurality of engine cylinders each having a 25 piston and a valve, of a rotatable shaft carrying wheels provided with ratchet teeth, means to successively operate the valves and actuated by the rotation of the shaft to a certain rotary position for each valve, and 30 means actuated successively by the pistons to

engage the ratchet teeth to turn the shaft successive portions of its movement to one of its several valve-operating positions.

5. In an engine, two engine cylinders each having a piston and a valve, a rotatable 35 shaft carrying two ratchet wheels each having two teeth, means actuated by the rotation of the shaft to a certain position to operate the valves, and means actuated by alternate movements of each piston to engage 40 a tooth of a ratchet wheel to rotate the shaft.

6. In an internal combustion engine, the combination of cylinders having valves and pistons, a cam-shaft having valve-operating cams, ratchet wheels carried on the cam- 45 shaft, rock lever arms pivoted concentric the cam-shaft and having pallets engaging the ratchet wheels, and means intermediate said pistons and said arms to rock the arms by the movement of the pistons to turn the cam- 50 shaft successive portions of its movement to one of its valve-operating positions.

In testimony whereof I have hereunto set my hand in presence of two subscribing witnesses.

JOHN R. WARREN.
